UNITED STATES PATENT OFFICE.

JOSEPH ANDRASSY, OF CLEVELAND, OHIO.

VENTILATOR.

1,333,651.

Specification of Letters Patent. Patented Mar. 16, 1920.

Application filed August 20, 1919. Serial No. 318,645.

To all whom it may concern:

Be it known that I, JOSEPH ANDRASSY, a citizen of the United States, residing at Cleveland, in the county of Cuyahoga and State of Ohio, have invented a certain new and useful Improvement in Ventilators, of which the following is a full, clear, and exact description, reference being had to the accompanying drawings.

10 This invention relates to ventilators and more particularly to the type used on ships for ventilation between and below decks and has for its object the provision of a ventilator adapted for use in stormy or heavy 15 weather as well as ideal weather.

Another object is to provide means for producing a forced draft so that in calm or stormy weather a more uniform ventilation is thereby secured.

20 With these and other objects in view, the invention consists in the various novel features of construction and arrangement of parts shown in the accompanying drawing in which—

25 Figure 1 is a front elevation of my device with the storm doors thrown open; Fig. 2 is a similar view with the storm doors closed; Fig. 3 is a sectional view on the line 3—3 of Fig. 2, Fig. 4 is a sectional view on the line 4—4 of Fig. 3 and Fig. 5 is an enlarged sectional view of the mouth of the ventilator.

30 The ventilator consists of the usual upright stack 1 fitted at its base with the reinforcing band 2 so that the stack can be rotated by the handles 3 about a projection from the deck (not shown). The upper end of the stack is provided with a cowl 4 having its opening or mouth 5 fitted with a pair 35 of storm doors 6. The doors 6 are preferably hinged to the sides of the cowl by hinge members 7 so that when opened the doors fold back and present a small surface and consequently offer little resistance to the 40 wind, as shown in Fig. 1.

45 The mouth of the cowl has a finishing bead 8 about its periphery which is preferably rounded on its outer surface and flattened on the inner side, so as not to materially reduce the diameter of the cowl mouth and thus interfere with the supply of air to the ventilators when the doors are open, the bead being also flattened on its forward side so as to present an abutment for the doors 50 when closed. A lug 9, carrying a bearing 10 is preferably formed integral with the

bead at the lower edge of the mouth of the cowl, the purpose of which will be fully described later.

55 The doors 6 are provided with openings 11 which are covered on the outer face of the doors by hoods 12 having bottom openings 13. The periphery of the inner face of each of the doors is provided with a rubber gasket 14 held in place by suitable 60 fastenings such as the clips 15. A pair of latch members 16 serve to hold the doors in the closed position. It will be noted that the edges of the doors overlap one another when closed, as shown in Fig. 4, thereby 65 presenting a substantially water-tight covering at the mouth of the cowl but at the same time allowing air to be admitted through the openings 13 and 11 to the ventilator stack.

70 75 A fan member 17 mounted on a shaft 18 is journaled at one end in the bearing 10 and at the other end in a bearing 19 fastened to the wall of the cowl. The fan may be driven in any suitable manner from below, 80 as by a motor (not shown) connected to the fan shaft by a belt 20. Thus in stormy weather, when the doors are closed, a forced draft may be secured; or in calm weather the doors may be left open and the fan operated to secure the desired ventilation.

75 It will be readily apparent that I have provided a ventilator which is equally efficient under all weather conditions and capable of producing the desired ventilation at 85 all times.

Having thus described my invention, what I claim is:

1. A ventilator comprising a stack member and a cowl member fastened thereto, a shaft journaled in the throat of said cowl, a fan member fastened to said shaft, a pair of doors hingedly connected to the sides of said cowl member, said doors being provided with a plurality of air ports there-through, each air port having a hood extending downwardly from its upper edge and inclosing the said edge and the side edges of said port, and means for driving said fan member.

100 105 110 2. A ventilator comprising a stack member and a cowl member fastened thereto, a fan positioned in the throat of said cowl, a pair of water tight doors hingedly connected to the sides of said cowl, said doors being adapted to overlap when closed and assume a stream line position when open.

against the sides of the cowl and means for driving said fan member.

3. A ventilator comprising a stack member and a cowl member fastened thereto, a bead surrounding the edge of the mouth of said cowl, said bead being flat on its forward and inner sides, a pair of water tight doors hingedly connected to the sides of said

cowl and adapted to abut against said bead when closed and assume a stream line position against the side of said cowl when open, a fan journaled in the throat of said cowl and means for driving said fan. 10

In testimony whereof, I hereunto affix my signature.

JOSEPH ANDRASSY.
